United States Patent Office

Des. 198,868

Patented Aug. 11, 1964

198,868

CASE FOR BEVERAGE BOTTLES OR THE LIKE

Robert L. Beesley and Rudolph H. Matthias, Saginaw, Mich., assignors to The Dow Chemical Company, Midland, Mich., a corporation of Delaware

Filed Jan. 6, 1964, Ser. No. 78,095

Term of patent 14 years

(Cl. D58—5)

Fig. 1

Fig. 2

FIG. 1 is a perspective view of a case for beverage bottles or the like, showing our new design; and

FIG. 2 is a bottom plan view thereof.

The dominant features of our design reside in the portions shown by full lines. The portions of the side and end walls not shown in FIGURE 1 are the same as those illustrated.

We claim:

The ornamental design for a case for beverage bottles or the like, as shown and described.
